UNITED STATES PATENT OFFICE

EDWARD L. HARRINGTON, OF ERIE, PENNSYLVANIA, ASSIGNOR TO G. H. WILLIAMS COMPANY, OF ERIE, PENNSYLVANIA, A CORPORATION OF PENNSYLVANIA

GRAPPLE

Application filed October 29, 1926. Serial No. 144,957.

Grapples for handling such material as sugar cane require an extended series of grappling teeth and difficulty has been experienced in making such structures rigid enough to sustain the strains incident to the operation of the tool to prevent over-weight of the implement. The present invention is designed to simplify such a device as to its operation and also to make possible a much lighter tool with the same capacity. Features and details of the invention will appear from the specification and claims.

The invention is illustrated in the accompanying drawings as follows:—

Fig. 1 shows an end elevation of the grapple closed.

Fig. 2 a side elevation of the grapple.

Fig. 3 an end view of the grapple open.

Fig. 4 a diagram of the threading of the closing cable through the closing sheaves.

Fig. 5 a section on the line 5—5 in Fig. 2.

1 marks a pivot rod for the grappling jaws and 2 and 3 grappling teeth, or jaws arranged at intervals along the rod and alternating with each other as clearly shown in Fig. 2. Bars 4 and 5 extend through the jaws 2 and 3 at the bends of the jaws. Links 6 extend from the rods 4 and 5 to a rod 7 which forms the head of the grapple.

Bifurcated closing arms 8 extend from the teeth 2 and sheaves 9 are mounted on the ends of these arms by means of pins 10. A hoisting cable 11 extends from a mounting 12 around a sheave 13. The sheave 13 is mounted on a pin 14 carried by a plate 15 which is bent upon itself and around the rod 7. The end of the cable 11 is carried over a drum 16 by means of which the hoisting cable is operated.

A closing cable 17 extends from the mounting 12 past a guide sheave 18 mounted on the rod 7, over a sheave 19, over a sheave 20 carried by a block 21. The block 21 is in the form of a plate folded upon itself around a bolt 21^a which in turn is secured to a hanger 22 carried by the rod 7. The cable 17 extends from the sheave 20 under and around the sheave 9 and is returned over a sheave 23 carried in a block 24 formed of a plate mounted on a rod 25 which in turn is

mounted on the hanger 22. The line 17 then passes over the sheave 23 carried in a block 26^a, the block being mounted on the hanger 22 by means of the rod 25. The line 17 then passes under and around a pulley 29, which is at the end of the tooth adjacent to the arm having the sheave 19 and back past the guide pulley 30 on the shaft 7, and thence over an operating drum 31.

The device operates in a manner common to such devices in a general way, that is to say, by slackening the closing line the grappling hooks, or teeth are opened and by drawing on the closing line pressure is put upon the arms 8 and this operating as a lever not only tends to close the teeth 2 but to draw the pivot bar 1 upwardly within the links 6 and thus draw the teeth together. The sheaves extending lengthwise of the device are swingingly mounted so that they readily maintain their alignment with the sheaves on the closing arms.

By thus applying the power to each of the closing arms a rigid frame construction uniting the several arms is avoided and thus a comparatively light structure may be used with ample power for the purpose.

Preferably the teeth are arranged in a double series, one at each end of the machine, and each having a duplicate mechanism such as described. The hoisting and closing lines on both series operate on the drums 16 and 31 respectively.

What I claim as new is:—

1. In a grapple, the combination of a series of connected pairs of pivoted jaws arranged side by side; sheaves on a plurality of the jaws at one side of the series, said sheaves having their axes parallel with the axes of the jaw pivots; sheaves having their axes in a plane at right angles to the axis of the jaws; and a closing line operating on said sheaves, said line being carried from a sheave on one jaw to a sheave on another jaw by the sheaves having their axes at an angle to the axis of the jaws.

2. In a grapple, the combination of two series of connected pairs of pivoted jaws arranged side by side; sheaves on a plurality of the jaws at one side of each series, said

sheaves having their axes parallel with the axes of the jaw pivots; sheaves having their axes in a plane at right angles to the axis of the jaws; and closing lines for each series operating on said sheaves, said line being carried from a sheave on one jaw to a sheave on another jaw by the sheaves having their axes at an angle to the axis of the jaws.

3. In a grapple, the combination of a series of three pairs of pivoted connected jaws arranged side by side; sheaves on each of the jaws at one side of a series, the axes of the sheaves being in alinement with the axes of the pivots of the jaws; a head; sheaves mounted on the head; and a closing line extending around the sheave of the middle jaw, over a sheave on the head, under a sheave on an end jaw, over sheaves on the head and under the sheave on the opposite end jaw.

20 In testimony whereof I have hereunto set my hand.

EDWARD L. HARRINGTON.
